STORAGE RECEPTACLE UNIT

Robert S. Shelly, Logan, Utah

Application May 7, 1956, Serial No. 41,383

Term of patent 14 years

(Cl. D58—12.6)

Fig. 1 is a perspective view looking toward the front, one side, and the top of a storage receptacle unit embodying my new design.

Fig. 2 is a front elevation.

Fig. 3 is a side elevation showing the front and the rear end portions as they appear when looking from the left in Fig. 1, the intermediate portion being broken away for convenience of illustration.

The characteristic features of my design for the storage receptacle unit disclosed reside in the end portions having the configuration shown in full lines.

I claim:

The ornamental design for a storage receptacle unit, substantially as shown and described.
